UNITED STATES PATENT OFFICE.

JOHN GAMBER AND OTTO F. HEER, OF WASHINGTON, PENNSYLVANIA.

INFANT'S BED.

No. 823,271.

Specification of Letters Patent.

Patented June 12, 1906.

Application filed December 11, 1905. Serial No. 291,243.

To all whom it may concern:

Be it known that we, JOHN GAMBER and OTTO F. HEER, citizens of the United States of America, residing at Washington, in the county of Washington and State of Pennsylvania, have invented certain new and useful Improvements in Infants' Beds, of which the following is a specification, reference being had therein to the accompanying drawings.

10 This invention relates to certain new and useful improvements in cribs; and the invention has for its primary object to combine a crib and bed, whereby either one can be used independently of the other.

15 Our invention aims to provide a crib and bed particularly adapted for children, and in constructing the crib and bed we have embodied novel means whereby the crib may be used as a "jumper" or amusement device 20 for children. In this connection means have also been devised whereby the crib can be reciprocated to produce a motion similar to a rocking crib. To this end we have combined a crib and bed in a compact form, which will 25 be extremely simple in construction, strong and durable, and free from all danger of being injured by constant use.

With the above and other objects in view, which will more readily appear as the nature 30 of the invention is better understood, the same consists in the novel construction, combination, and arrangement of parts to be hereinafter more fully described and then specifically pointed out in the claims, and, referring to the drawings accompanying this application, like numerals of reference designate corresponding parts throughout the several views, in which—

Figure 1 is a plan of our improved crib. 40 Fig. 2 is a side elevation of the same. Fig. 3 is a cross-sectional view on the line $x-x$ of Fig. 1. Fig. 4 is a similar view showing the crib in position to be used as a bed. Fig. 5 is a similar view showing the crib as an amusement device, and Fig. 6 is a perspective view 45 of a prop or brace that is used in connection with the crib.

To put our invention into practice, our improved crib consists of four standards or 50 posts, the posts 1 1 forming the head of the crib and the posts 2 2 the foot of the crib.

The posts 1 1 and 2 2 are adapted to be connected together by transverse bars 3 and 4, while the posts 1 and 2 upon each side of the 55 bed are connected together by longitudinally-

disposed rails 5 and 6. Between the bars 3 and 4 and 5 and 6 are arranged a plurality of vertically-disposed rounds or slats 7, the structure so far described forming a substantially rectangular framework. 60

Secured to the vertically-disposed rounds upon each side of the crib are longitudinally-disposed strips 8, said strips being located intermediate the rails 5 and 6 upon each side of the crib. Hinged to said strips, as at 9, 65 are rectangular frames 10 10, said frames when not in use being folded upwardly against the sides of the crib, as clearly illustrated in Figs. 1 to 3, inclusive, but when being used are adapted to fold downwardly to form a 70 central horizontally-disposed partition, the inner edges of the frames 10 10 being held by blocks 11 11, carried by the end rounds or slats 7 of the crib. The frames 10 10 are adapted to form a horizontal partition upon 75 which a spring-frame may be placed or a mattress to form a bed adapted to be used by children. 80

Within the structure thus described is mounted an auxiliary crib 12, consisting of side frames 14 14 and end frames 15 15. The auxiliary crib is supported by a plurality of coiled springs 16, said springs being secured to the side rails 6 6 of the main structure or crib and to the sides and corners of the auxiliary crib. 85

Surrounding the auxiliary crib 12 is a telescopic frame, said frame consisting of rods 17 17, adapted to slide into tubes 18 18. The tubes 18 and the rods 17 are connected to the 90 lower edges of the auxiliary crib by coiled springs 19. The top rails 5 5 of the main structure or crib are provided with a plurality of hooks 20, the object of which will be presently described. 95

In Figs. 1 to 3, inclusive, we have illustrated the crib in condition to be used, whereby the auxiliary crib 12 can be used as a bed for an infant, while in Fig. 4 of the drawings the frames 10 10 are in position to form a bed-frame above the auxiliary crib 12. When the auxiliary crib 12 is to be used as an amusement device or jumper, the frames 10 10 are folded upwardly, as shown in Fig. 5 of the drawing, and the telescopic frame which surrounds the auxiliary crib is elevated and placed in engagement with the hooks 20, carried by the top side rails 5 of the main structure or crib. The elevation of the telescopic frame elevates the auxiliary crib 12, 110

expanding the springs 16 and 19, which support the auxiliary crib 12 in practically the position shown in Fig. 5. When the auxiliary crib is in this position, it can be reciprocated or moved to give its occupant a rocking effect.

We have provided one of the side frames 14 of the auxiliary crib with a strap 21, the free end of which can be fastened to the opposite end of the auxiliary crib to retain an infant in one end of the crib. The opposite end of the auxiliary crib may be made stationary by using a strap 23, said strap being fixed to one end of the auxiliary crib, while the free ends of the strap may be detachably connected at one end of the crib, this strap being employed to hold one end of the crib while the opposite end of crib is being used as a jumper. When it is desired to hold the crib stationary in an elevated position, such as illustrated in Fig. 5 of the drawings, props 22 may be inserted between the sides of the auxiliary crib and the main crib or frame, said props bracing the auxiliary crib on all sides to hold it stationary.

In the present illustration the crib is constructed of wood, and it is obvious that the entire structure may be made of light and durable metal.

Such changes in the construction and operation of the crib as are permissible by the appended claims may be resorted to without

departing from the spirit and scope of the invention.

What we claim, and desire to secure by Letters Patent, is—

1. A crib embodying a rectangular framework, frames hinged to the inner sides of said framework and adapted to fold inwardly to form a horizontal partition, an auxiliary crib resiliently suspended within said framework, a telescopic frame surrounding said auxiliary crib and resiliently connected to said crib, means to detachably connect said telescopic frame to the upper edges of said framework, substantially as described. 35

2. In a crib, the combination with a framework, of frames hinged to the inner sides of said framework and adapted to fold inwardly, an auxiliary crib resiliently supported in said framework, a telescopic framework surrounding said auxiliary crib and resiliently connected to said auxiliary crib and means projecting from the framework to support the telescopic frame in elevated position, substantially as and for the purpose described. 40 45

In testimony whereof we affix our signatures in the presence of two witnesses.

JOHN GAMBER.
OTTO F. HEER.
